YARN CHANGER

James E. Burgess, Summerville, Ga., and Archibald W. Roney, Philadelphia, Pa., assignors to Fidelity Machine Company, Wilmington, Del., a corporation of Delaware

Application September 17, 1934, Serial No. 744,450

10 Claims. (Cl. 66—140)

This invention relates to yarn changers for knitting machines, preferably a rib machine making hosiery tops, for providing a pattern of horizontal stripes in the finished rib product.

5 It is an object of this invention to provide the yarn changer with means whereby at least three or more guides or fingers are automatically moved into and out of their operative positions with a view to providing the object knitted with a pattern of horizontal stripes of three or more colors or kinds or weights of yarn.

10 It is also an object of this invention to provide means for cutting and main and auxiliary means for thereafter holding or clamping the ends of those yarns not being knitted at any given time together with pattern means for the desired selective actuation of the yarn guides and the clamp and cutter.

15 The above and other objects are obtained as hereinafter set forth, reference being had to the accompanying drawings, in which,

20 Fig. 1 is a plan view of part of a circular rib knitting machine, illustrating the yarn changer as applied thereto,

25 Fig. 2 is a side elevation of the machine,

Fig. 3 is an enlarged plan view of the clamping and cutting unit,

30 Fig. 4 is an enlarged side view of the same unit,

Fig. 5 is an enlarged end view of the same unit and,

35 Fig. 6 is a disassembled view of the elements comprising the unit.

In the drawings, 1 represents the fixed bed plate of a circular knitting machine, preferably a rib machine of the type having vertical cylinder and horizontal dial needles, which has the rotary cam ring or box 2 carrying the usual vertically extending posts connected at their upper ends by the usual bracket through which

40 passes the usual dial post 3 to which the usual stationary needle dial is fastened. Surrounding the dial post is the rotating dial cam 4 and indicated at 5 is the stationary needle cylinder. These and other parts of the usual rib machine form no portion of the present invention. While a machine with a revolving cam box has been illustrated, it will be obvious that the yarn changer is equally adapted for use on the type of machine in which the needle cylinder rotates and the cam box remains stationary.

45 On the upper face of the cam box 2 is positioned the plate 6 by means of posts 7, 7 fastened to the plate and extending into holes in the cam box whereby the yarn changer may be adjusted vertically. To the plate 6 is fastened the

block 18 by means of screws 8, 8 passing through circumferential slots in the plate. By loosening these screws and by means of these slots the yarn changer may be adjusted circumferentially. Secured to the block 18 by screw 20 is a second block 19 having a tongue and groove connection as shown, extending radially of the machine. By loosening screw 20 the yarn fingers and clamp and cutter may be adjusted radially of the cylinder, since this block carries both of these units as will be pointed out.

50 The block 19 is formed with a flat face lying in a plane preferably at an angle of about 30 degrees to the horizontal and into which is placed the shoulder screw 9 so that it extends perpendicular to said face. The shoulder screw 9 forms a pivot for at least three yarn fingers 10, 11 and 12, although a greater number might be used if desired. Each of these fingers includes a long arm having at the end a yarn feeding eye 13 and if desired the feeding end may be wider as at 14 on finger 10 whereby there is sufficient room for two yarn eyes therein for use in feeding two yarns simultaneously as in plating. At the other end of the yarn fingers are the selecting butts or projections 15, 16, and 17, whereby the fingers are selectively moved into action when the projections are moved by the selecting device (to be described) to cause the fingers to move clockwise, Fig. 1, about their pivot.

55 Also secured in the face of the block 19 is the pivot 22 upon which the latches 23, 24 and 25 are mounted so as to be in the same planes as the fingers 10, 11 and 12, with which they cooperate respectively, each latch having a latching portion 27. Each latch has a cut out face and in this face and surrounding the pivot 22 is a coil spring 26, one for each latch. One end of each spring 26, Fig. 1, takes in back of a yarn finger catch 21 urging the finger in a counter-clockwise direction. The stops for the fingers are the faces 28 of the latches against which the faces 29 of the yarn fingers rest as they are urged by the springs 26. The other end of each spring takes against the side wall of the cut out face (not shown) in each latch, urging the same in a counterclockwise direction. The ends of the latches fit into the bottom of the U-shaped member 30, which is pivotally mounted on 22 by means of holes in the side walls of the U shape. The force of the ends of the latches against the U-shaped member 30 urges the same to also move counterclockwise against the stop 31 fastened to the post 22. When the member 30 is moved (by means to be described acting on

edge 32) in a clockwise direction, it forces all the latches to also move in a clockwise direction sufficiently far so that any finger in action whose catch 21 has been held by a latching portion 27 will be released and will move counterclockwise under action of spring 26 to an idle position against stop 28. Any other finger which has been moved into action will bring its catch 21 within range of its latch, so that when member 30 and the latches are allowed to return to normal position, the latch pertaining to the finger then moved into action, will hold that finger in active position by reason of its hold on the finger catch. The member 30 is released while the newly selected finger is still held in, as will be explained when the selecting means is described.

In addition to the yarn guides, the block 19 carries a plate 33 slotted for the reception of a screw 34 whereby it is clamped in place so that upon loosening said screw it may be moved in a direction generally toward or from the guides. Said plate is also slotted for the reception of a second screw 35 whereby there is clamped to it a block 36 providing a bearing for a bolt 37 inclined in a line substantially parallel to that of the screw or pivot 9, it being noted that the slot for the screw 35 extends in a line substantially at right angles to that of the screw 34 in order that the block 36 may be adjusted toward or from the center line of the machine.

On the bolt 37 is fixed the main and auxiliary clamping means indicated generally at 38 in Fig. 1, and shown in detail in Figs. 3, 4 and 5. On the bolt 37 are three fixed plates 39, 40 and 41 each having one elongated arm and two shorter arms respectively fitting on opposite side faces of block 36, thus keeping themselves stationary with respect to the block. The member 39 has the end of its elongated arm offset as at 42, the undersurface of which end acts as a clamp in a manner to be described. The member 40 provides the pivot 43 on its elongated arm for the auxiliary clamping hook like member 44 having the U shaped base by means of which the member is movable about pivot 43. The spring 45, Fig. 3, around the pivot and taking against block 36 and against the U shaped base, urges the member 44 counterclockwise, so that the offset hook end 46 of the member 44 is held against the side face of the elongated arm of the member 40. Thus an auxiliary clamp is provided between 46 and 40 to hold the yarns once they are forced therebetween (by means to be described), Fig. 6. The member 41 has the elongated arm 47 whose upper surface acts as a clamp in a manner to be described and whose under surface acts as a fixed shear blade cooperating with a movable shear blade to be described.

Between members 39 and 40 is the link 48 and between members 40 and 41 is the clamping element 49 and below the member 41 is the movable shear blade 50. Each of the members 48, 49 and 50 have rearwardly extending arms in which there are holes to receive the operating arm 51 shown in dotted lines in Fig. 5. This arm 51 causes the clamp 49 and cutter 50 to be moved about the pivot 37 to cut and clamp the yarn.

The link 48 functions as a guide member for arm 51 to keep the same parallel to pivot 37. The member 49 has an elongated arm terminating in a U shaped member 52 which overlies the elongated arm of member 40 as shown in Fig. 3. The upper outside face of the U shaped member 52 cooperates as a clamp with the under-surface of arm 42, causing the yarn to be bent

as shown diagrammatically in Fig. 6 at 53. Actually the bent portion of the yarn is gripped between these two clamping surfaces when the clamp is closed. The lower outside face of the U shaped member 52 cooperates as a clamp with the upper surface of arm 47 causing the yarn to be bent as shown diagrammatically at 54. As the yarn is clamped by the U shaped member 52 between itself and 42 and 47, it is forced between the hook 46 and the member 40, Fig. 6, by the shape of the cut out 55, Fig. 3, on the member 52. Thus the yarns are held by the main clamp and by the auxiliary clamp so that during the time the main clamp is open, as when releasing a yarn for knitting, or when about to receive a retired knitting yarn, the yarns will be held by the auxiliary clamp.

All of the members on the pivot 37 are held in place below block 36 by means of the spring 56, the washer 57 and the pin 58, which cooperate with the pivot 37 above block 36. The arm 51 which operates the clamp and cutter is threaded into square member 62, thus providing for adjustment. The arm is guided by a hole in plate 63 fastened to block 19 by screw 64 passing through a slot. By loosening the screw the plate may be adjusted. A spring 65 between the arm 51 and plate 63 normally retains the clamp and cutter in closed position. When the arm 62 is forced inwardly the clamp and cutter is opened.

The yarn fingers are intended to each occupy either of two positions in one of which the thread is so directed as to be engaged by the cylinder needles and knitted and in the other of which the thread is held away from the cylinder so that it cannot be engaged by the needles the ends being in the clamp and cutter. As each finger is moved outwardly to idle position, the yarn extends from the last needle taking the same to the yarn eye, and the fingers are so positioned when idle that this extent of yarn is in the range of the opened clamp 52 and the opened cutter 50. These are opened each time a yarn is to be changed. As the clamp and cutter close, the yarn is acted upon as described. A new yarn thrown into action is drawn out of the auxiliary clamp as the needles start to knit.

To one side of the machine is the selector element 67 which may be moved to any one of four levels by any usual pattern means acting on post 69. There are three active levels in each of which one of the projections 15, 16, or 17 of the yarn fingers will be actuated by 67 to make that finger active. At the fourth or idle level no fingers are actuated. Secured to the under-surface of element 67 is the latch releaser 68, which element strikes face 32 of member 30, causing the latches to be released. Face 32 is sufficiently long and below the fingers so that it is actuated by 68 when any one of the three fingers are actuated. It is to be noted that the selector 67 extends further circumferentially than does 68, so that the selected finger is held in until the latches are allowed to come back into action. Secured to the upper surface of the selector 67 is the member 66 which operates the clamp and cutter against spring 65. This member 66 is likewise operative only in the three levels of the yarn fingers. The action of the latch release 68 is delayed with respect to the yarn finger selector, thus allowing for a yarn overlap of the outgoing and the incoming yarns over a few needles.

We claim:

1. A yarn changer and clamp and cutter for a knitting machine having a plurality of fingers

for feeding a plurality of yarns, means for moving the fingers to active and inactive positions, a main clamp for holding the yarns comprising a plurality of clamping surfaces, an auxiliary clamp between the said plurality of clamping surfaces and a yarn cutter.

2. A yarn changer and clamp and cutter for a knitting machine having a plurality of fingers for feeding a plurality of yarns, means for moving the fingers to active and inactive positions, a main clamp for holding the yarns comprising a plurality of fixed clamping surfaces and a single movable element having clamping surfaces cooperating with said fixed clamping surfaces, an auxiliary clamp between the fixed clamping surfaces, and a yarn cutter.

3. A yarn changer and clamp and cutter for a knitting machine having a plurality of fingers for feeding a plurality of yarns, means for moving the fingers to active and inactive positions, a main clamp for holding the yarns comprising a plurality of fixed clamping surfaces and a single movable U shaped element, the side walls of the U acting as clamping surfaces cooperating with said fixed clamping surfaces, an auxiliary clamp between the fixed clamping surfaces and between the side walls of the U when the main clamp is closed, and a yarn cutter.

4. A yarn changer and clamp and cutter for a knitting machine having a plurality of fingers for feeding a plurality of yarns, means for moving the fingers to active and inactive positions, a main clamp for holding the yarns comprising a plurality of clamping surfaces, an auxiliary clamp between the said plurality of clamping surfaces, means on the main clamp causing the yarns to be placed in the auxiliary clamp as the main clamp is closed, and a yarn cutter.

5. A yarn changer and clamp and cutter for a knitting machine having a plurality of fingers for feeding a plurality of yarns, means for moving the fingers to active and inactive positions, a main clamp for holding the yarns comprising a plurality of clamping surfaces having fixed and movable parts, an auxiliary clamp between the said plurality of clamping surfaces, the movable part of the main clamping surfaces causing the yarns to be placed in the auxiliary clamp, and a yarn cutter.

6. A yarn changer and clamp and cutter for a knitting machine having a plurality of fingers for feeding a plurality of yarns, means for moving the fingers to active and inactive positions, a

main clamp for holding the yarns comprising a plurality of fixed clamping surfaces and a single movable U shaped element, the side walls of the U acting as clamping surfaces cooperating with said fixed clamping surfaces, an auxiliary clamp between the fixed clamping surfaces and between the side walls of the U when the main clamp is closed, the movable U shaped element causing the yarns to be placed in the auxiliary clamp as the main clamp is closed, and a yarn cutter.

7. A yarn changer and a clamp and cutter for a knitting machine having at least three fingers for feeding at least three yarns, means for moving the fingers to active and inactive positions, a main clamp for holding the yarns comprising a plurality of clamping surfaces, an auxiliary clamp between the said plurality of clamping surfaces, and a yarn cutter.

8. A yarn changer and a clamp and cutter for a knitting machine having a plurality of fingers for feeding a plurality of yarns, means for moving the fingers to active position, latches for holding the fingers in active position, means to release the latches to allow the fingers to return to inactive position, a main clamp and cutter for holding the yarns comprising a plurality of clamping surfaces, an auxiliary clamp between the said plurality of clamping surfaces, and a yarn cutter.

9. A yarn changer and clamp and cutter for a knitting machine having a plurality of fingers for feeding a plurality of yarns, the fingers being inclined at an acute angle to the center line of the cylinder, means for moving the fingers to active and inactive positions, a main clamp for holding the yarns comprising a plurality of clamping surfaces, an auxiliary clamp between the said plurality of clamping surfaces, and a yarn cutter.

10. A yarn changer and clamp and cutter for a knitting machine having a plurality of fingers for feeding a plurality of yarns, the fingers being inclined at an acute angle to the center line of the cylinder, means for moving the fingers to active and inactive positions, a main clamp for holding the yarns comprising a plurality of clamping surfaces, an auxiliary clamp between the said plurality of clamping surfaces and a yarn cutter, the main clamping members being inclined at substantially the same acute angle as the fingers.
